UNITED STATES PATENT OFFICE.

ANSEL P. PHILLIPS, OF PROVIDENCE, RHODE ISLAND, ASSIGNOR TO
FREDERICK I. MARCY, OF SAME PLACE.

DESIGN FOR A SLEEVE-BUTTON.

SPECIFICATION forming part of Design No. 14,260, dated September 4, 1883.

Application filed March 13, 1882. Term of patent 7 years.

To all whom it may concern:

Be it known that I, ANSEL P. PHILLIPS, of the city and county of Providence, and State of Rhode Island, have invented and produced 5 a new and original Design in Sleeve-Buttons, of which the following is a full, clear, and exact description, reference being had to the accompanying drawing, forming part of this specification.

10 The figure is a view of a button having my newly-designed face engraved upon it, consisting in a bird, branches of grass, and an ornamented segment of a circle, the ground being formed of parallel straight lines cut so as to relieve the design.

15 Buttons for cuffs have been heretofore engraved with various designs, and the ground-work has usually been roughened or stippled. Such roughening or stippling did not relieve 20 the design clearly. And in some instances the ornamentation has been in relief, the ground being provided with engine-ruling.

25 The leading feature of my design consists in engraving in outline upon the polished surface of the button the border A and the ornamenta-

tion C, which consists of a bunch or spray of grass partially concealed by the figure of a bird, and in front of the bird an ornamental segment, as shown. The groundwork B for the design is formed of a number of fine parallel lines extending from the border A to the outline of the ornamental figures C. The ridges between the parallel lines of the ground or field are in the same horizontal plane as the surface of the border and ornaments; but 35 as the ruled lines of the ground are cut below said plane the border and ornamentation will have the appearance of being in relief. The ornamentation left after lining the ground or field may be engraved, as shown. 40

I claim—

The hereinbefore-described design, consisting of the border A, the ornamental figures C, and the ground or field consisting of fine parallel lines extending from the border to the 45 edges of the ornamental figures.

ANSEL P. PHILLIPS.
